UNITED STATES PATENT OFFICE.

WITOLD CHYLEWSKI, OF LEMBERG, AUSTRIA.

AUTOMATIC PISTOL.

1,224,902.

Specification of Letters Patent.

Patented May 8, 1917.

Application filed March 22, 1916. Serial No. 85,818.

To all whom it may concern:

Be it known that I, WITOLD CHYLEWSKI, engineer, of 10 Kadecka, Lemberg, Austria, having invented certain new and useful Improvements in Automatic Pistols, do hereby declare the following to be a full, clear, and exact description of the same.

My invention relates to automatic pistols comprising an auxiliary movable finger-piece used for retracting the slide.

It is well-known to provide repeating pistols in front of the trigger proper with a second or auxiliary finger-piece which when drawn backward coacts with the slide and enables the first cartridge to be brought out of the magazine into the barrel and thus makes the weapon ready for firing without the aid of the other hand. This arrangement has, however, the defect that in order to be able to fire the weapon after it has been loaded in this manner, it is necessary to remove the first finger from the said auxiliary finger-piece and place it on the trigger, an operation which occupies much time and in the moment of excitement may also readily not succeed.

A primary object of my invention is to provide a repeating or automatic pistol of the type described to which this defect is not attached.

Accordingly I provide that the slide which has been retracted by the second finger-piece is released in a predetermined position and flies back, the arrangement being such that the second finger-piece is then located immediately in front of the trigger, bears against the same and can be used for firing the weapon.

To this end the invention consists in the construction, arrangement and combination of parts described hereinafter and pointed out in the claims.

One embodiment of my invention and a modification thereof are represented by way of example in the accompanying drawing, wherein:

Figure 1 is a side elevation of one form of my improved automatic pistol in one position,

Fig. 2 is a like view thereof in another position,

Figs. 3 and 4 are end and side elevations, respectively, of the auxiliary finger-piece, and

Fig. 5 shows the essential parts of a modified form in side elevation.

Referring firstly to Figs. 1 to 4, the auxiliary or second finger-piece 1 is rigidly connected with two parallel bars or guides 2 guided in the frame of the pistol. A spring 3 which bears against these guides or bars tends to return the finger-piece 1 into its normal position shown in Fig. 1 as soon as the pressure of the first finger is diminished. When the first finger presses against the finger-piece 1 its two elastic hooks 4 take into the body of the slide 5 and pull the latter against the action of its spring back into its rear position shown in Fig. 2, in which the cartridge in the magazine projects so far that it is seized by the returning slide and inserted into the barrel, the slide is returned into its normal position owing to the slanting faces 6 of the elastic hooks 4 abutting against fixed stops 7 in the extreme retracted position of the auxiliary finger-piece and, sliding against these stops, being turned downward, so that their sharp edges release the slide and allow it to fly back into its normal position. The auxiliary finger-piece remains in its retracted position and, when pulled farther, abuts against the trigger so that the latter can be moved and one shot after another can be fired. The spring 3 tends to drive the auxiliary finger-piece forward so that the alternating play between the pressure of the finger and the force of the spring causes the auxiliary finger-piece to move to and fro, which is suitable for the delivery of a succession of shots. When the first finger is removed from the auxiliary finger-piece the latter returns into its normal position, whereupon the pistol can be employed in the same manner as any other.

In the modification shown in Fig. 5 the auxiliary finger-piece 1, connected with the bars 2, carries two inwardly projecting pins 9 slidable in grooves 10 in the frame 11. The rear end of each bar 2 is formed like a catch 12 and has a slanting face 13, and each of these catches coacts with a shoulder 14 of the slide 15; a fixed stop 16 coacts with the face 13. When the first finger is pressed against the spring-pressed auxiliary finger-piece the latter is rocked somewhat so that the catch 12 takes into the shoulder 14 and the slide 15 is driven when the finger-piece is drawn backward. Near the end of this movement the slanting face 13 abuts against the fixed stop 16 so that the finger-piece is rocked in the opposite direction and the

slide 15 is released and flies back under the action of its spring.

I do claim:—

1. In an automatic pistol, the combination of a frame provided with a stop, a forwardly spring-pressed slide slidable on the frame, a trigger mounted in the frame, and a finger-piece slidable along the frame, adapted to engage with said slide and drive the same into its rear position, said finger-piece being adapted to coact with said stop and to be thereby released from said slide when the finger-piece is directly in front of said trigger.
2. In an automatic pistol, the combination of a frame provided with a stop, a forwardly spring-pressed slide slidable on the

frame, a trigger mounted in the frame, and a finger-piece slidable along the frame, said finger-piece carrying an elastic hook adapted to engage with said slide and drive the same into its rear position, said hook being adapted to coact with said stop and to be thereby released from said slide when the finger-piece is immediately in front of said trigger.

In testimony that I claim the foregoing as my invention, I have signed my name in presence of two subscribing witnesses.

WITOLD CHYLEWSKI.
